UNITED STATES PATENT OFFICE.

SAMUEL MOORE, OF SCUNTHORPE, ENGLAND.

GAS GENERATOR.

1,418,158.

Specification of Letters Patent. Patented May 30, 1922.

Application filed December 7, 1921. Serial No. 520,670.

To all whom it may concern:

Be it known that I, SAMUEL MOORE, a subject of the King of Great Britain and Ireland, and a resident of Scunthorpe, 5 county of Lincoln, England, have invented a certain new and useful Improvement in Gas Generators, of which the following is a specification.

This invention relates to gas generators of 10 the kind in which water gas and coal gas are produced in one and the same apparatus, which apparatus comprises a generator or producer having a vertical retort, made of a smaller cross-sectional area, in its upper 15 part surrounded by a chequered chamber, primary and secondary air blasts being employed, the latter being utilized to burn the gases from the blow in the chequered chamber surrounding the retort, the whole being 20 enclosed in a surrounding shell, and fuel being supplied from the top through a coal valve.

Said invention consists essentially in the provision, in combination, in gas generators 25 of the above-expressed kind, of a fuel feeding valve-controlled hopper and a coke or ash discharging mechanism at the top and bottom respectively of the apparatus, heating chambers for the passage therethrough 30 of the secondary air blasts, and a series of chequered regenerators wherein combustion takes place, as hereinafter described and shown in the accompanying drawings.

In carrying out the invention, there is no 35 internal water contact with the gas, so there is consequently no loss of ammonia, while the very hot lean gas rises into immediate and intimate contact with the comparatively cool rich gas in the retort and absorbs valuable 40 gaseous enrichments which would otherwise be deposited as liquids. Again, the gas is given a long travel through the retort and is subsequently very gradually cooled, thus ensuring high thermal results with the consequent advantage that a very large volume 45 of gas is obtainable per ton of coal carbonized and an economy in coal is thereby effected.

And in order that the said invention may be 50 fully understood, it will now be described with reference to the accompanying drawings and figures and letters of reference marked thereon, that is to say:

Figure 1 is a sectional elevation of a combined vertical coal gas retort and water gas generator constructed in accordance with 55 this invention.

Figure 2 is a sectional plan view on line 2, 2, Figure 1; and

Figure 3 is a sectional elevation of the 60 apparatus at right angles to Figure 1.

In a practical embodiment of this invention, the water-gas section B is arranged underneath the retort A, and both are enclosed in a single metal shell a. A feeding 65 hopper C at the top of the device ensures a continuous supply of fuel. At the bottom of the generator B a discharging mechanism D is arranged which extracts the coke or ash, and can be worked for any desired 70 quality of coke; or, if complete gasification of the fuel is desired, the ash can be discharged at will and all clinker entirely prevented.

The plant can be run day and night for 75 weeks without stopping. It can be started up from cold in a few hours, or it can be shut down at night, or during week-ends, or started to full work again within half an hour.

No outside producer is required, as a primary and a secondary air blast E and F respectively are employed to maintain the carbonizing temperature. The secondary air is passed through a heating chamber P where 85 it meets the blow gases, combustion takes place in a series of chequered regenerators H¹, H², H³, and the "blowing" period is reduced to a minimum. Liquid hydrocarbons can be injected at K, Figure 1, if extra en- 90 richment is required.

An overhead bunker L is provided which, being supplied with suitable coal, allows the fuel to drop by gravity to the rim of the feeding hopper C above mentioned. A 95 coal valve C¹ fitted to the top of said hopper C is opened or shut by means of a light chain (not shown) which reaches down to the operating stage. This valve C¹ is opened at stated intervals (according to the 100 through-put required), and the hopper recharged with coal. The discharging gear D is operated by a lever D¹ on the operating stage. Longer or shorter intervals occur between each discharge according to the degree of carbonization preferred. The "blow" lasts about one minute and the run about 6 minutes, and the cycle may be continued during charging or discharging operations without need for shutting down.

Steam is admitted at four points marked respectively E¹, E², E³, E⁴,—see particularly Figure 3. The steam entering at the top of the generator shell at E¹ passes through a

superheating chamber J and thence to the top of the retort A. Travelling down the retort it sweeps the coal gas down into the water gas zone, where the mixed gases are 5 blended and fixed before exit. The steam admitted at E² at the base of the snift pipe travels through the regenerators H¹, H², H³, and enters the bottom of the retort through the combustion gas nostrils P. This steam 10 ejects any explosive gases remaining in the regenerator flues after each run.

The steam admissions E¹ and E² serve for the down runs, while those at E³ and E⁴ are for the up runs. At E⁵ steam is admitted 15 occasionally mainly for the purpose of quenching the coke before reaching the receiver D. Through steam admission E⁶ steam passes into the primary air inlet pipe E, whence it passes through the blast circulator Q and into the generator by the blast ducts E.

Coming in contact with the incandescent coke in the generator, it combines to produce water gas.

25 When "up" steaming is "on" the primary air valve is "off."

When the water gas is produced as aforesaid, it travels upward into immediate contact with the coal gas produced in the retort, 30 and thence to the top gas outlet R through the steam superheating chamber J. On the down run, the steam entering at the top as aforesaid, travels through the coal gas and water gas zones and enters the blast ducts E, 35 and thence by way of the blast circulator Q passes through the bottom gas outlet S. The travel of the gas is through the same ducts as the upward steam and primary air but in the opposite direction and at different intervals. The outcoming gas heats 40 the blast circulating chamber and the incoming air and, in sequence, the incoming steam.

The primary air (blast) enters the lower 45 portion of the generator at the blast ducts E and passes out at the nostrils P at the base of the retort—see Figure 3. The secondary air enters at F and is conducted to the secondary air-circulating chamber G and 50 thence through ports to the bottom of the regenerator H¹. The primary and secondary air blasts meet at the bottom of the generator H¹ and produce combustion. The resulting flame is kept in contact with the 55 outside of the gas retort and produces sufficient heat to carbonize the coal in the retort. The products of combustion are carried up the regenerator H¹, down H², up H³ and out by the snift valve I.

60 Heat is so well retained by the regenerators aforesaid that only about one minute is required for the "blow."

For town use, the gas has two exits, one at top of the apparatus (up run exit R) 65 and the other at the bottom thereof (down

run exit S). Both outlet pipes enter a washbox T where a valve (not shown) on the end of the pipe S and on the end of the pipe R¹ in communication with the exit pipe R are sealed in gas liquor and operated separately by iron rods (not shown) terminating with a lever handle outside.

When gas-making on the up run, one handle opens the required valve, while the other valve remains closed. On the down 75 run, the operation is reversed. In either case, the outgoing gas passes to the outlet U of the washbox and on to the gas holder.

I claim:—

1. In gas generating apparatus of the class 80 described, a retort, a series of regenerating chambers surrounding said retort and annularly arranged with respect to each other, a decomposing chamber beneath said retort, and means for introducing air and steam 85 into said last mentioned chamber.

2. In gas generating apparatus of the class 90 described, a retort, a series of annularly arranged regenerating chambers surrounding said retort and communicating with each other at alternate ends to thereby provide a tortuous passage therethrough for the products of combustion, a decomposing chamber beneath said retort, and air and steam inlets above and below said decomposing chamber.

3. In gas generating apparatus of the class 100 described, a retort, a regenerating chamber surrounding said retort and comprising concentrically arranged chambers communicating at opposite ends, forming a tortuous passage for the products of combustion, a decomposing chamber beneath said retort, an air inlet at the top of said regenerating chamber communicating through the regenerating chamber with the decomposing chamber at the base of the retort, and a steam inlet at the top of said regenerating chamber communicating with said retort.

4. In gas generating apparatus of the class 110 described, a retort, a regenerating chamber surrounding said retort, a decomposing chamber beneath said retort, air and steam inlets at the base of the decomposing chamber, and air and steam inlets at the top of 115 said regenerating chamber for alternating up and down runs.

5. In gas generating apparatus of the class 120 described, a retort, a series of annularly arranged regenerating chambers surrounding 120 said retort, a superheating chamber at the top of said regenerating chambers, a decomposing chamber beneath said retort, and air and steam inlets above and below the decomposing chamber.

In testimony whereof I have hereunto affixed my signature this 15th day of November 1921.

SAML. MOORE.
